(**) Term: **14 Years**

(21) Appl. No.: **29/406,688**

(22) Filed: **Nov. 17, 2011**

CLAIM

The ornamental design for stackable trays for an epistaxis treatment kit, as shown and described.

(51) **LOC (9) Cl. 03-01**

(52) **U.S. Cl.**

USPC D3/203.1

(58) **Field of Classification Search**

USPC D3/201-205, 901, 903, 904-905, D3/313-314, 295, 304; 206/534.1, 535, 538; D7/553.2, 553.3, 553.4, 554.3, 555; 220/500-501, 212, 662, 665, 575; D24/227; D22/136; D19/75

FIG. 1 is a front perspective view of the stackable trays for an epistaxis treatment kit showing our new design;

See application file for complete search history.

FIG. 2 is a front perspective view of the upper tray.

FIG. 3 is a top plan view of the upper tray.

FIG. 4 is a front elevational view of the upper tray.

FIG. 5 is a right side elevational view of the upper tray.

FIG. 6 is a left side elevational view of the upper tray.

FIG. 7 is a bottom plan view of the upper tray.

FIG. 8 is a rear elevational view of the upper tray

FIG. 9 is a front perspective view of the lower tray.

FIG. 10 is a top plan view of the lower tray.

FIG. 11 is a right side elevational view of the lower tray.

FIG. 12 is a left side elevational view of the lower tray.

FIG. 13 is a bottom plan view of the lower tray.

FIG. 14 is a rear elevational view of the lower tray; and,

FIG. 15 is a front elevational view of the lower tray.
